[57] CLAIM

The ornamental design for a toy house, substantially as
shown and described.

DESCRIPTION

FIG. 1 is a front perspective view of a toy house with
the door in an opened condition showing our new de-
sign;

FIG. 2 is a right-side elevational view with the door in
a closed condition shown on a slightly enlarged scale;

FIG. 3 is a rear elevational view thereof; and

FIG. 4 is a bottom plan view thereof.

FIG. 1

FIG. 2

FIG. 3

FIG. 4
